UNITED STATES PATENT OFFICE

2,619,285

FUEL CONTROL SYSTEM

Charles O. Everhart, Cleveland, Ohio

Substituted for application Serial No. 549,134,
July 7, 1931. This application December 7,
1949, Serial No. 131,645

5 Claims. (Cl. 236—26)

1

In the combustion of fluid for heating boilers or for any other purpose, it is desirable, from an economic standpoint, to feed the ingredients of combustion to the burner in the proper ratio and also in the proper quantity that will insure maximum efficiency of the burner. It is also essential that the quantity of the mixture supplied to the burner may be varied from time to time to accommodate different varying boiler conditions while still maintaining the proper ratio of the ingredients of the mixture. Under certain conditions it is also desirable to maintain a substantially constant pressure in the fuel supply line and to vary this pressure only in so far as changing boiler conditions create a demand for a lesser or greater quantity of fuel.

The improved fluid regulator comprising the present invention is adapted to deliver from different sources the various ingredients of combustion in the proper ratio and in the proper quantity to accommodate changing boiler conditions or to accommodate varying demands for fuel at the burner.

In carrying out the principles of the invention, a regulating valve is disposed in each supply line which conducts the ingredients of combustion to the burner. These valves are so arranged and assembled in an operative unitary regulator structure that they may be jointly controlled to reduce or increase the quantity of the ingredients of combustion supplied to the burner. The factor which simultaneously controls the operation of the valves is selected boiler condition. Preferably these valves are controlled by the steam pressure of the boiler at the outlet. Thus when a load is thrown upon the boiler, requiring consequently a greater amount of steam, the valves are simultaneously opened to admit a greater quantity of the ingredients of combustion to the burner without destroying the proper ratio of these ingredients as they are delivered. Conversely when the load on the boiler is dropped off, the valves are simultaneously closed to admit a lesser quantity of the ingredients of combustion to the burner while still maintaining the predetermined ratio at which these ingredients are delivered. In this application the pressure developed by the boiler at the output has been chosen as the controlling factor for opening or closing the valves but it is to be distinctly understood that other boiler conditions may be selected to accomplish this feature. For example, a pressure generator of the type disclosed in the patent to Andrews 1,396,239, patented November 8, 1921, for a water flow device or of the type disclosed in the patent to Veen schoten

1,759,146 patented May 20, 1930 for a feed water valve, may bridge the water level in the boiler and this pressure generator may serve to develop pressure for operating the valves in accordance with the water level in the boiler. Under certain conditions it may be necessary that the supply of the ingredients of combustion to the burner may be manually controlled according to the discretion of the operator. Toward this end the invention contemplates the provision of a regulator for supplying ingredients of combustion to a burner which is selectively operable either by varying boiler conditions or manually. As stated before it is desirable that when the quantity of the ingredients of combustion delivered to the burner is increased or decreased, a predetermined ratio be maintained between these ingredients of combustion. The improved regulator is also provided with means whereby this ratio may be varied as occasion demands so that a greater or lesser proportion of any one ingredient of combustion may be maintained.

In the boiler room of commercial plants and on board large steam propelled ships there is usually one operator or superintendent invested with the authority and duty to see that the boilers are operated under ideal conditions. Other employees, including executives, frequently obtain notions as to how the boiler should be operated and very often without authority they attempt to make adjustment of the boiler regulating system. The present regulator is provided with means for preventing an unauthorized person who does not possess the proper adjusting tool from making adjustment to the regulator system. Thus the entire system is protected against amateur experimenters.

Other objects and advantages of the invention not at this time more particularly enumerated will become more readily apparent as the nature of the invention is better understood, and the same consists in the novel construction, combination, and arrangement of parts shown in the accompanying two sheets of drawings in which:

Fig. 1 is a side elevation of the improved regulator;

Fig. 2 is a diagrammatic view showing the regulator installed in a fuel supply system;

Fig. 3 is a side elevation of an adjusting tool employed in connection with the present invention;

Fig. 4 is an enlarged detailed side elevation of an adjusting mechanism employed in connection with the present invention.

Fig. 5 is a rear view of the regulator, showing

the manual controlled means for operating the same.

In all of the above described views like characters of reference are employed to designate like parts throughout.

Referring now to Figure 2 a boiler, which it is desired to maintain under substantially even conditions of pressure, is designated at 10. This boiler is provided with a steam outlet or header 12. The regulator is designated in its entirety at 14 and comprises a cylinder 16 having a piston 18 slidably mounted therein. The cylinder is connected by a suitable conduit 20 to the header 12 to permit fluid pressure developed in the header 12 to be admitted to the underneath side of the piston 18. The burner for the furnace (not shown) which heats the boiler 10 is designated at 22. This burner is provided with an air inlet 24 adapted to be connected to an air supply line 26 for the introduction of air to the burner, for admixture with the fuel. An inlet 28 is adapted to be connected to a fuel supply line and an inlet 32 is adapted to be connected to a fluid supply line 34 which permits the introduction of an atomizing fluid such as air or steam to the burner.

The fuel supply line 30 has interposed therein a valve 36 and the fluid line 34 has interposed therein a valve 38. Both of these valves are operative instrumentalities of the regulator 14. The air supply line 26 has interposed therein a valve 40 of the butterfly type and this latter valve also is an operative instrumentality of the regulator 14.

Associated with the regulator 14 is a vertically movable cam plate 42 having adjustable cam members 44 and 46 thereon adapted to engage projecting plungers 48 and 50 respectively for operating the respective valves 36 and 38. The cylinder 16 has associated therewith a plunger 96 which engages a depending stem 52 on the plate 42 to cause movement of this latter plate and cause the cam members 44 and 46 to simultaneously engage the plungers 48 and 50 to operate the valves 36 and 38 simultaneously to admit a greater or lesser quantity of fuel to the burner in a predetermined ratio. A second stem 54 projects upwardly from the plate 42 and is provided with a collar 56 having engagement with a rifled stem 58, to which stem is secured a pivotal closure member 60 within the casing of the valve 40. Upward movement of the plate 42 rotates the rifled stem 58 and opens or closes the closure member 60 to admit a greater or lesser quantity of air for admixture at the opening with the fuel, in a predetermined ratio.

Referring now to Figure 5, it will be seen that the plate 42 is adapted to be raised or lowered by hand. Accordingly a lever 62 is pivoted at 64 intermediate its ends. The upper edge 66 of this lever is adapted to engage a pin 68 secured to a plate 42 so that depression of the other end of the lever 62 will serve to raise the plate 42 for operating the valves 36, 38 and 40 simultaneously. A pawl 70 is pivoted to the lever 62 and co-operates with a ratchet plate 72 to hold the lever 62 in any desired adjusted position. Normally when the regulator is being automatically controlled from the pressure developed in the header 12, the pawl remains out of engagement with the ratchet plate 72 as shown in Fig. 2. The above description has been given from a diagrammatic representation of the device and from this description and operation of the regulator is readily apparent. It will be seen that movement of the plate 42 in one direction or the other will serve

to admit a greater or lesser quantity of the ingredients of combustion in a predetermined proportion to the burner as the pressure in the header 12 of the boiler 10 varies. A description of the details of construction of the improved regulator will disclose the specific operation of the regulator and will show the manner in which the proportions of the ingredients of combustion admitted to the burner may be varied.

Referring now to Figure 1 the regulator is supported upon a base 74 from which there projects a standard 76 to which a piston and cylinder assembly 78 is secured. This assembly comprises an open ended tubular cylinder 78 threaded externally at opposite ends as at 80 and 80'. A pair of cup shaped cap members 82 and 84 serve to close the ends of the cylinder 78. The piston 18 is of the leather cup type and consists in a plate 86 to the underneath side of which is secured a leather cup 88 by means of a washer and bolt which projects into one end of a piston rod or plunger 94. The bolt serves to retain the piston rod or plunger 94 in position on the piston 18. The upper end of the rod 94 is provided with a reduced portion 96 which extends through a threaded sleeve 98 which is threaded into the cap 87 centrally thereof. The reduced portion 96 of the plunger 94 is freely slideable through this threaded sleeve. The sleeve 98 is provided with a head 100 having apertures 102 therein for adjusting the height of the sleeve to limit the downward movement of the stem 52 and consequently limit the open position of the valve 36, 38 and 40.

The cap 87 is provided with a boss 104 which is externally threaded and receives thereon a supporting ring 106 provided with a threaded aperture through which the boss 104 extends. The ring is provided with a plurality of apertures 108, 110, and 112 for supporting the valves 36, 38 and 40 respectively. Each of the valves 36 and 38 consists in a casing 114 having a removable and reversible valve seat 116. The seat 116 is normally closed by a closure member 118 having stems 120 and 122. The closure member 118 is normally maintained on its seat by means of an adjustable spring arrangement 124 controlled by an adjustable screw 126. However, any required adjustment of the spring arrangement 124 may only be effected by means of the adjusting tool 128, as shown in Fig. 3.

The forward end of the stem 122 is engageable by one end of a sliding plunger 130 which projects from the casing. The casing 114, is provided with a chamber 132 communicating with the outlet and with the inlet of the valve. Sliding movement of the plunger 130 inwardly of the casing will cause the inner end of the same to engage the stem 122 and move the closure member 118 from its seat. When the plunger 130 is released the closure member 118 is urged by the action of the adjustable spring mechanism 124 on to its seat to assume its normally closed position. The valves 36 and 38 are each held in diametrically opposed relation on the circular supporting member 106 by means of lock nut 136.

Extending diametrically and vertically across the circular supporting member 106 is a strap 138. Secured to this strap medially of the ends thereof is a fixed guide plate 140, in which is vertically slideable the plate 42. The plate 42 has pivoted thereto cam members 44 and 46 which are provided with straight cam surfaces 142 and 144 respectively which are adapted to bear against the ends of the plungers 130 of the valves 36 and 38.

to force these plungers inwardly of their respective valve casings as the plate 42 moves upwardly. The cam members 44 and 46 are secured in their pivotal relation with respect to the plate 42 by means of screws 146 similar to the adjusting screw 126, which extend through slots in these cam members.

A pair of externally pivoted adjusting members 150 and 152 are secured on the plate 42 and these members are adapted to be secured in any adjusted position by means of adjusting screws 154 similar to the adjusting screws 156. The adjusting members 150 and 152 are adapted to engage the inner surface of the cam members 44 and 46 and to limit the inner inwardly swinging movement of same. The adjusting members 150 and 152 may be provided with calibrations 158 co-operating with calibrations 156 in order that the cam members 44 and 46 may be accurately and scientifically adjusted in accordance with good engineering practice. By adjusting the cam members 44 and 46 properly the inclination of the straight cam surfaces 142 and 144 may be varied to maintain the proper proportional pressure drop across the valves 36 and 38 to admit the ingredients of combustion to the burner in a desired proportion in a greater or lesser quantity. In order to prevent free movement of the cam members 44 and 46 a compressed spring 160, the convolutions of which are held in alignment by means of a guide rod, is inserted between the lower ends of these members.

The stem 54 which is secured to the slideable plate 42 is provided with an enlarged portion 164 through which there extends a lock bolt 166 similar to the adjusting screw 126. This lock bolt engages a sleeve 168 having a coined head 170. This sleeve 168 is keyed to the stem 58 and by backing up on the lock nut 166 the sleeve 168 may be rotated manually to adjust the throw of the sleeved stem 58 to which the butterfly closure 60 is secured in the valve casing 40. Upward movement of the plate 42 and stem 54 and sleeve 168 will cause rotation of the rifled stem 58 to open the butterfly closure 60 in the casing of the valve 40 while at the same time the cam members 44 and 46 will force the stems 130 of the valves 36 and 38 into their respective casing and open these valves. Downward movement of the sliding plate 42 will cause a reverse operation of the three valves 36, 38 and 40.

It will be seen that the valves 36 and 38 may be independently adjusted while the valve 40 may also be adjusted independently and thus any desired ratio of opening of the three valves may be effected to create different pressure drops across the valve openings to supply the ingredients of combustion to the burner in varying proportionate quantities.

Vertical movement of the plate 42 may be effected by means of the arrangement of parts shown in Figure 5 which has previously been described hereinbefore. The pin 68 is in the form of a bolt similar to the adjusting screw 126. This bolt extends through a slot 172 in the strap 138. A pin 174 also similar to the adjusting screw 126 has secured thereto one end of a tension spring 176 and the other end of this tension spring is secured to the pin 68 to normally urge the plate 42 downwardly. The pawl 70 is provided with a pair of depressions 180 and 182 which cooperate with a projection or pin on a leaf spring 184 and extending through the lever 162 in contact with the pawl to hold the latter in its operative or inoperative position. In its operative position the

5 pawl 70 engages the teeth on the ratchet plate 72 secured to the supporting member 176 to hold the lever 162 in any adjusted position and to hold the plate 42 at an elevation commensurate with the position of the lever as previously described. In its inoperative position, with the projection on the leaf spring 184 resting in the depression 180, the pawl does not engage the teeth on the ratchet plate 72 and the operation of the regulator is automatic.

10 When the pressure in the header 12 of the boiler 10 is increased, this pressure is transmitted to the underneath side of the piston 18 thereby moving this piston upwardly against the 15 action of the coil spring 94. The plunger 94 is moved upwardly into engagement with the stem 52 and the plate 42 is accordingly elevated thereby operating the valves to close the valves 36, 38 and 40 simultaneously.

20 On the other hand, a decrease in pressure in the header 12 will cause a corresponding decrease in pressure on the underneath side of the piston 18 and the same will be moved downwardly under the action of the coil spring 94' together 25 with the plunger 94 and plate 42, thereby operating the valves simultaneously to admit more of the ingredients of combustion to the burner 32 to develop more steam in the boiler 10 and again 30 raise the pressure in the header 12. It will be seen therefore that under normal conditions of operation the tendency is to maintain a constant pressure in the header 12. When there is a demand for steam due to an increased load on the 35 boiler the improved regulator causes a greater quantity of the ingredients of combustion in the proper proportion to be supplied to the burner. When there is little demand for steam as for example where the boiler is run under conditions of small load the improved regulator will 40 supply a lesser quantity of ingredients to the burner while steam maintains the desired proportion of supply.

The adjusting screws 126, the lock bolts 166 and 154 and the studs 146, 174 and 68 are in the 45 form of the special adjusting screws and may be adjusted or moved only by an authorized person who is equipped with the adjusting tool shown in Fig. 3. Thus the entire regulator is protected against unauthorized adjustment.

50 I have presented and submitted my invention, as described and shown, in a design and structure that provides an efficient operating mechanism, however adaptations of the device to various requirements in use may necessitate modifications or changes in design or structure or both, without departing from the scope of the 55 appended claims.

The subject matter disclosed herein is identical with that submitted in the application previously filed on July 7, 1931, Serial No. 549,134, and later abandoned.

What I claim as new and desire to secure by Letters Patent is:

60 1. The combination of a boiler system including a boiler and a burner therefor having fluid supply lines leading thereto of a valve disposed in each supply line one of said valves being of the butterfly type and having a rifled stem secured to the closure member thereof, another of 65 said valves being of the plunger operated type, a movable cam plate having a cam member thereon adapted to cooperate with said plunger to move the same, a sleeve secured to said movable 70 cam plate said sleeve engaging said rifled stem,

for rotating the latter and means controlled by given boiler conditions for moving said cam plate.

2. The combination of a boiler system including a boiler and a burner therefor having fluid supply lines leading thereto of a valve disposed in each supply line, one of said valves being of the butterfly type and having a rifled stem secured to the closure member thereof, another of said valves being of the plunger operated type, a movable cam plate having a cam member thereon adapted to cooperate with said plunger to move the same, a sleeve secured to said movable cam plate said sleeve engaging said rifled stem for rotating the latter; means controlled by given boiler conditions for moving said cam plate, and manual means for moving said cam plate.

3. The combination of a boiler system including a boiler and a burner therefor having fluid supply lines leading thereto of a valve disposed in each supply line, one of said valves being of the butterfly type and having a rifled stem secured to the closure member thereof, another of said valves being of the plunger operated type, a movable cam plate having a cam member thereon adapted to cooperate with said plunger to move the same, a sleeve secured to said movable cam plate said sleeve engaging said rifled stem for rotating the latter; means controlled by given boiler conditions for moving said cam plate and means for limiting the movement of said cam plate.

4. The combination of a boiler system including a boiler and a burner therefor having fluid supply lines leading thereto of a valve disposed in each supply line, one of said valves being of the butterfly type and having a rifled stem secured to the closure member thereof, another of said

valves being of the plunger operated type, a movable cam plate having a cam member thereon adapted to cooperate with said plunger to move the same, a sleeve secured to said movable cam plate said sleeve engaging said rifled stem for rotating the latter; means controlled by given boiler conditions for moving said cam plate; means for limiting the movement of said cam plate; and means for manually moving said cam plate.

5. The combination of a boiler system including a boiler and a burner therefor having fluid supply lines leading thereto of a valve disposed in each supply line, one of said valves being of the butterfly type and having a rifled stem secured to the closure member thereof, another of said valves being of the plunger operated type, a movable cam plate having a cam member thereon adapted to cooperate with said plunger to move the same, a sleeve secured to said movable cam plate said sleeve engaging said rifled stem for rotating the latter; means controlled by given boiler conditions for moving said cam plate, and means for adjusting the cam member on said cam plate.
